TRIMMER TAB CONTROL FOR AIRPLANES

James Martin, Higher Denham, near Uxbridge,
EnglandApplication March 9, 1942, Serial No. 434,013
In Great Britain March 15, 1941

1 Claim. (Cl. 244—90)

This invention relates to the adjustment and mounting of trimmer tabs on elevators, ailerons, rudders or other control members of airplanes, and has for its chief object to enable fine and positive adjustments of a trimmer tab relatively to its elevator or other appropriate airplane part to be effected from a conveniently accessible point. Another object of this invention is to obviate extraneous fitments for the setting and locking of the trimmer tabs and also to isolate substantially the whole of the adjusting and locking means from a trimmer tab in such manner that there is the minimum gap between the trimmer tab and elevator or equivalent member and no projecting parts affecting the streamline continuity of the tab and elevator or equivalent member. A still further object of this invention is to support the adjusting and locking means by parts of the aircraft which will ensure a firm mounting and the minimum of vibrational and other shocks liable to upset the trimming or to produce looseness in the elements of the adjusting means.

In carrying one form of this invention into practice as applied to a trimmer tab on an elevator, the tab is suitably journaled at its leading edge across side ribs of the elevator and at one end has fixed to it a lever projecting forwardly into the elevator and connected by a link to a lever supported for oscillation within the elevator in juxtaposition to the trailing end opening in the elevator which receives the tab. This latter lever is connected in turn by a longitudinal push rod to a screw jack, the appropriate rotary threaded element of which is driven from a spindle mounted in bearings in diametrically opposed parts of a main supporting sleeve, bush or shaft of the elevator, suitable universal joints being provided with the spindle to compensate for changes effected in the direction of the axis of the push rod and jack and also to enable the spindle to be driven by a tool inserted through an opening in the leading edge of the elevator. A similar arrangement may be employed with a trimming-tab mounted in a rudder or other control member of an airplane.

In order that this invention may be clearly understood and readily carried into effect drawings are appended hereto illustrating an embodiment thereof as applied to an elevator, and wherein,

Fig. 1 is a broken side elevation view partly in section of the trimmer tab adjusting means and the manner of supporting it within the elevator.

Fig. 2 is a broken detail part sectional side elevation view to a larger scale showing the screw-

jack manipulating and adjusting means for the trimmer tab.

Fig. 3 is a broken plan view of Fig. 2.

Referring to the drawings the skin or outline of the elevator is indicated by the broken lines 1, and the inner and outer ribs 2 and 3 respectively of one side of the elevator are likewise shown in broken lines, these being made use of in the mounting of the trimming mechanism. The shaft carrying the elevator (shown broken in Figs. 2 and 3) is indicated by the reference numeral 4 and the trimmer tab by the reference numeral 5.

The trimmer tab 5 is a close fit in the opening 6 in the trailing end of the elevator and fixed to one of its side edges close to its leading edge is a forwardly directed arm 7 forming a lever by which the trimmer tab is adjusted about the axis of a pair of lateral spigots 8 fixed to the tab and supported in ball or other bearings 9 carried by the trailing ends of the rib 2. The arm 7 can be an integral part of one of the plates 10 riveted to the trimmer tab and carrying the spigots 8.

The arm 7 projects forwardly into the elevator and passes through a narrow slot in the transverse or stepped part 2a of the rib 2 forming a front corner of the opening 6 so that the arm 7 does not project above or below the skin of the elevator. Leverage is imparted to the arm 7 to angularly adjust the trimmer tab from a remote control device situated at the forward end of the elevator, and the appropriate connection to this remote control device is by means of a link 11 connecting the free end of the arm 7 to the free end of a lever 12 receiving one end of a push rod 13 and pivoted at its other end between a pair of plates 14 welded to a cross tube 15 fixed by end plates 16 to the ribs 2 and 3 of the elevator. The other end of the push rod 13 forms part of a screw jack, for which purpose it is formed with an internally threaded sleeve 17 into which is threaded a screw threaded shaft 18 adapted to be rotated to apply fore and aft traverse to the push rod 13. The three pivots of the connections of the arm 7 link 11 and lever 12 provide a triangulated arrangement (see Fig. 2) which with the push rod 13 affords an automatic locking of the trimmer tab in any of its positions of adjustment.

The means for rotating the screw 18, and comprising the said remote control device, comprises a spindle 19 firmly mounted for rotation in bearing bushes 20 fixed in a pair of diametrically opposed bosses 21 integral with the sleeve 22 fixed across the ribs 2 and 3 and mounted upon the beforementioned shaft 4.

The connection of the screw 18 to the spindle 19 is by means of a universal joint 23, and a similar joint 24 is fitted to the front end of such spindle to enable the spindle to be driven by a key or crank inserted at a convenient angle through an opening in an accessible part of the leading end of the elevator, the front element of the universal joint 24 being adapted to receive the key or crank. Or, alternatively, the said front element can receive a sprocket or flexible shaft or be otherwise adapted for operation from a remote control such as e. g. trimmer tab adjusting means close to the pilot's seat. Access to the pivots of the link 11 and lever 12 can be effected through an opening 25 in the rib 3, the pivotal joints preferably being screws 26 threaded at one end into bosses 27 formed in the appropriate parts of the link, lever and push rod, the latter having a bifurcated head 13a to receive the link 11 and lever 12. Likewise access to the screw jack and the universal joint 23 can be effected through an opening 28 in the rib 3, such arrangement of openings and location of elements facilitating assembly and inspection. The spindle 19 may be operated by a short shaft connected to the front universal

joint 24 and journalled in the leading edge of the elevator. The forward end of the shaft being shaped for engagement by an operating key or shaft.

5 I claim:

In an airfoil, the combination of, an aileron, a trimmer tab pivotally mounted on the trailing edge of said aileron, a horn centrally disposed on and rigidly fixed to the forward part of the trimmer tab and projecting forwardly through a slot into the trailing edge of said aileron, a link having one end pivotally mounted to the end of said projecting part of said horn, a second link positioned inside the trailing edge of 10 said aileron and having one end pivotally mounted therein, a screw-threaded jack positioned inside said aileron having an elongated shaft extending rearwardly inside the trailing edge of said aileron, the other ends of said links being 15 pivotally connected to said shaft at a common point to give a triangulated disposition of the pivots which furnishes spacial rigidity, positive 20 control of the trimmer tab, and divides the force applied to said shaft by the trimmer tab.

25 JAMES MARTIN.
